FISH HOOK BEND CORRECTOR

Benjamin P. Robinson, Springfield, N.J.
(1101-C Council Oak Drive, Sioux City, Iowa 51109)

Filed Mar. 16, 1973, Ser. No. 342,152

Term of patent 14 years

Int. Cl. D22—05, 99
U.S. Cl. D22—31

FIG. 1

FIG. 2

FIG. 3

FIG. 4

FIG. 5

FIG. 6

FIG. 7

FIG. 1 is a perspective view of my design for fish hook bend corrector.

FIG. 2 is a view of one side of the device shown in FIG. 1.

FIG. 3 is a front view of the device shown in FIG. 1 and also shows in dotted lines a fish hook for illustrative purpose only, placed in a position to be straightened in the device.

FIG. 4 is a view of the other side of the device shown in FIG. 1.

FIG. 5 is a top view of the device shown in FIG. 1.

FIG. 6 is a bottom view of the device shown in FIG. 1.

FIG. 7 is a rear view of the device shown in FIG. 1.

I claim:

The ornamental design for a fish hook bend corrector, as shown and described.
